CLAIM

The ornamental design for a charger as shown and described.

DESCRIPTION

FIG. 1 is a bottom front perspective view of a charger showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the charger in an environment in which it may be used;

FIG. 10 is a perspective view thereof showing the charger in another environment in which it may be used; and,

FIG. 11 is a perspective view thereof showing the charger in another environment in which it may be used.

The broken lines in the figures show portions of the charger and environment that form no part of the claimed design. The Figures are illustrated to show contrasting appearance. The claimed area shown in white is one appearance, the area shown in light gray is a second appearance, and the area shown in dark gray is a third appearance.
